(Cl. D87—3)

To all whom it may concern:

Be it known that we, Evelyn B. Steinberg and Dorris M. Scott, both citizens of the United States, residing at Los Angeles, in the county of Los Angeles and State of California, have invented a new, original, and ornamental Design for a Pin-On Purse or Similar Article, of which the following is a specification, reference being had to the accompanying drawing, forming part thereof.

Fig. 1 is a front elevational view of a pin-on purse or similar article showing our new design.

Fig. 2 is a side elevational view of the same.

Fig. 3 is a perspective view looking toward the front and slightly toward the right side thereof, in an open position.

Fig. 4 is an enlarged fragmentary detailed front elevational view of the upper right corner portion of the pin-on purse or similar article.

We claim:

The ornamental design for a pin-on purse or similar article, as shown.

EVELYN B. STEINBERG.
DORRIS M. SCOTT.
